UNITED STATES PATENT OFFICE.

MICHAEL ASLANIAN, OF LOS ANGELES, CALIFORNIA.

HARP FORK.

Application filed July 25, 1924. Serial No. 728,110.

To all whom it may concern:

Be it known that I, MICHAEL ASLANIAN, a citizen of Armenia, residing at Los Angeles, in the county of Los Angeles and State 5 of California, have invented new and useful Improvements in Harp Forks, of which the following is a specification.

This invention relates to stringed musical instruments, and more particularly it relates to harps.

An object of this invention is the provision of a hand-operated device which may be placed on a stringed musical instrument, such as a harp, for example, to shorten at 15 will a string of the instrument, a plurality of the devices being used—one for each string of the instrument.

Another object of this invention is the provision of a very inexpensive device for 20 the cheaper classes of harps, the device being used to shorten a string of the harp so as to raise the pitch of the string a semi-tone, and the device being adapted as a substitute for the expensive foot-operated mechanism 25 now employed on the more costly harps..

With the foregoing objects in view, together with such other objects and advantages as may subsequently appear, this invention consists in the construction and arrangement of parts hereinafter described and claimed and illustrated in the accompanying drawings, in which:

Figure 1 is a perspective view of a harp of conventional type, showing devices of my 35 invention positioned on the neck of the harp, each device being adapted to engage a string of the harp,

Fig. 2 is a perspective view of my device which may be called a fork, the same being shown in open or active position,

Fig. 3 is a view similar to Fig. 2, showing the device in closed or inactive position,

Fig. 4 is a section taken on the line 4—4 of Fig. 1,

Fig. 5 is a fragmentary front elevation of the neck of the harp, showing my device positioned thereon but in inactive position,

Fig. 6 is a view taken on the line 6—6 of Fig. 1, and corresponding to the view shown in Fig. 4, but showing the fork in the position in which it shortens a string, and

Fig. 7 is a view similar to Fig. 5, showing the fork engaging a string.

Referring to the drawings for a more detailed description thereof, the numeral 10

indicates a harp generally which comprises a curved neck 11 provided with tuning pins 12, to which are attached strings 12^a, and also comprises grooved bridges 13 below, and vertically offset from, the tuning pins 12 60 and against which the strings 12^a rest. The device or fork of my invention is clearly shown in Fig. 2 and comprises a back plate 14 having longitudinally thereof an elongated slot 15 and provided with side flanges 65 16, in the upper end of, and between, which is mounted a rotatable lever 17 beveled at its free end, as shown at 18 in Fig. 3, and having a groove 19 formed in the bevel 18. The lever 17 is provided with an arcuate handle 70 20. The back of the plate 14 may be provided with teeth 22, as shown in Figs. 4 and 6.

In positioning the fork, it is to be secured below the bridges 13 to the neck 11 by 75 screw 24 passing through the slot 15, the fork being positioned so that the length of the slot 15 is vertical and so that the lever 17 is uppermost. It will be seen that the teeth 22 on the back of the fork are pressed 80 into the neck and assist in holding the fork securely in position. The slot 15 is longer than the diameter of the screw 24 so that the fork may be adjusted exactly to the position required to raise the pitch of a string 85 a semi-tone, when the lever is moved to a horizontal position and the string 12^a engages the groove 19 of the lever. The device may be thrown into, or out of, engagement with a string, by manually turning the 90 lever 17 by the handle 20.

It will thus be seen that I have provided for a harp a fork for shortening a string so as to raise the pitch of the string a half tone, the fork being adapted to be thrown into, or 95 out of, engagement with a string by hand, and that the fork is adjustable longitudinally of the string so that it may be placed in exactly the right position.

While I have herein described one form 100 of my invention, modifications thereof may be devised without departing from the spirit thereof, and it is to be understood that such modifications come within the scope of this invention.

What is claimed is:

1. A harp fork for shortening a string and adapted to be thrown into or out of position by hand, said fork comprising a lever and means for pivotally mounting said lever 110

- upon the neck of a harp, said means providing an adjustment of the lever longitudinally of a string.
2. A harp fork for shortening a string and adapted to be thrown into or out of position by hand, said fork adapted to be adjustable longitudinally of a string of the harp.
3. A harp fork for shortening a string and adapted to be thrown into or out of position by hand, said fork adapted to be adjustable longitudinally of a string of the harp, and comprising a back plate having a slot longitudinally thereof and having outwardly extending side flanges and a lever mounted in and between said flanges.
4. A harp fork for shortening a string and adapted to be thrown into or out of position by hand, said fork adapted to be adjustable longitudinally of a string of the harp, and comprising a back plate having a slot longitudinally thereof and having outwardly extending side flanges and a lever mounted in and between said flanges, said lever having a groove to engage a string of a harp.
5. A harp fork for shortening a string and adapted to be thrown into or out of position by hand, said fork adapted to be adjustable longitudinally of a string of the harp, and comprising a back plate having a slot longitudinally thereof and having outwardly extending side flanges and a lever mounted in and between said flanges, said lever having a groove to engage a string of a harp, and provided with a handle.
6. A harp fork for shortening a string and adapted to be thrown into or out of position by hand, said fork adapted to be adjustable longitudinally of a string of the harp, and comprising a back plate having a slot longitudinally thereof and having outwardly extending side flanges and a lever mounted in and between said flanges, said lever having a groove to engage a string of a harp, and provided with a handle, said back plate having teeth on the back face thereof.

In testimony whereof I have signed my name to this specification.

M. ASLANIAN.
